UNITED STATES PATENT OFFICE

JONATHAN LUCAS, OF SAVANNAH, GEORGIA, AND ARTHUR F. CASE, OF CLEVELAND, OHIO, ASSIGNEES TO LUCAS-LAMBORN LOOM CORPORATION, OF NEW YORK, N. Y., A CORPORATION OF NEW YORK

SHUTTLE MECHANISM FOR LOOMS

Application filed June 22, 1928. Serial No. 287,518

Our invention relates to shuttle mechanism for looms and has for its object to provide a pair of reversely reciprocating supporting devices adapted alternately to engage and latch a shuttle in a novel manner whereby the latter is positively carried back and forth through the shed, the shuttle and the supporting devices being constructed in a manner to prevent interference or entanglement with the warp threads comprising the shed. A further object of the invention is to provide a novel form of shuttle having a compartment capable of accommodating a bobbin of large size, and having flanges extending laterally from said compartment, said flanges defining an open-ended housing within which the supporting devices travel. In addition, the invention contemplates a construction in which the transfer of the shuttle from one supporting device to the other is accomplished automatically at very high speed with a minimum of friction and in a uniform and positive manner, positive locking devices being provided to prevent premature release of the shuttle during such transfer. Other more specific objects will appear from the following description and the features of novelty will be pointed out in the claims.

Our present invention is an improvement on the shuttle mechanism disclosed in the United States patent to Jonathan Lucas No. 1,624,108, dated April 12, 1927.

In the accompanying drawings, which illustrate an example of the invention without defining its limits, Fig. 1 is a plan view of the shuttle and transfer mechanism, the shuttle being located at the center of the machine; Fig. 2 is a view in elevation of the parts shown in Fig. 1; Fig. 3 is a longitudinal vertical section on an enlarged scale through the shuttle and showing the carrier arms with their latching levers approaching each other; Fig. 4 is a view similar to Fig. 3 but showing the parts in a different position; Fig. 5 is a horizontal section on the line 5—5 of Fig. 3; Fig. 6 is a side view of the shuttle; Fig. 7 is a vertical transverse section on the line 7—7 of Fig. 6; Fig. 8 is a vertical longitudinal section through the bobbin compartment of

the shuttle; Fig. 9 is a view of the locking mechanism along the line 9—9 of Fig. 4; Fig. 10 is a section along the line 10—10 of Fig. 4 showing the guiding and supporting members for the latching levers; Figs. 11 and 12 are respectively a side view and a plan view of the tensioning mechanism; Fig. 13 is a rear view in elevation of a modification of the shuttle transfer mechanism looking at the same from the side opposite the shuttle; Fig. 14 is a plan view of Fig. 13; Figs. 15, 16, 17 and 18 are views in elevation showing the latching and locking mechanism of Figs. 13 and 14 in different positions as the latching levers approach each other; and Figs. 19, 20 and 21 show the latching and locking mechanism in different positions as the latching levers recede from each other after completion of the shuttle transfer.

In order that the following description may be more readily understood as it progressively unfolds, a general idea of the character of the motion of the shuttle which the operating mechanism produces will first be given.

The shuttle-operating mechanism about to be described operates in a similar manner to that disclosed in the patent above referred to. Stated generally, the operating mechanism acts continuously upon a shuttle, either through a pull or a push, to reciprocate the same positively through the shed of the loom transversely thereof, the shed being composed of warp threads running longitudinally of the loom in a manner well understood in the art. Upon the shuttle is mounted a bobbin from which the filler or weft thread unreels as the shuttle reciprocates through the shed, the filler being thus laid across the warp threads, after which it is compacted by the beater mechanism in the well-known manner. The reciprocating mechanism for carrying the shuttle back and forth across the machine comprises two reciprocating carriers, one at each side of the machine, which are operated to reciprocate between the center of the loom and their respective sides in opposed relation, i. e. they simultaneously approach and recede from the center of the machine. Each carrier is provided with means for supporting

55

60

95

100

the shuttle thereon and for latching the same thereto, so that as the carrier travels from the center to the side of the machine it may be considered as pulling the shuttle with it, 5 while as it returns from the side to the center of the machine, it may be regarded as pushing the shuttle before it. The latching devices on the carriers are arranged to cooperate with latching elements on the shuttle, and 10 the mechanism is so arranged and constructed, that as the carrier which supports the shuttle during a given stroke approaches the center of the machine, (as does also the other carrier) it is automatically unlatched from 15 the shuttle by the latching mechanism of the other carrier which thereupon becomes latched with the shuttle. As said other carrier travels back to its side of the loom it pulls the shuttle with it; and as it again approaches 20 the center of the machine upon reciprocation, a similar transfer of the shuttle takes place to the first-mentioned carrier. In this way the shuttle is given practically a continuous motion across the loom at high speed and in 25 a positive manner.

In Figs. 1 and 2 of the drawings we have shown a view of part of the actuating and supporting devices for the shuttle mechanism. The numeral 30 represents a portion 30 of the loom developed to constitute a guiding means extending transversely of the loom and below the usual shed formed of warp threads, as clearly shown in Fig. 5 of the aforementioned Patent No. 1,624,108, the 35 guiding means being so related to the shed as to permit the shuttle to be reciprocated through the latter as will be set forth more fully hereinafter. A pair of carriers 32 of suitable form and dimensions are slidably 40 mounted upon the guiding means 30 so as to be reciprocable thereon simultaneously toward and away from each other. The carriers may be reciprocated by any suitable mechanism such as, for instance, is shown and 45 described in the patent to Jonathan Lucas No. 1,623,258, issued April 5, 1927, in which case the carriers are connected with such mechanism by means of links 33. In the examples illustrated the carriers 32 include up- 50 rights 34 connected to horizontal members 35, and, as shown in Fig. 2, may be integral therewith. The carriers 32 may have any desired cross-section provided only that they are of sufficient strength to withstand the 55 repeated shocks and strains to which they are subjected, and in the form illustrated they have the cross-section of an I-beam cut away at 36 to reduce the weight thereof. The angular portions 37 of the carriers are preferably beveled or curved, as shown, so that the outer surfaces are smooth and free of projections of any kind.

For the purpose of facilitating an understanding of the shuttle and the carrying and transfer mechanism, to which our present in-

vention relates, the same will be described under the following general headings:

I. Embodiment shown in Figs. 1 to 10.

- A. Shuttle.
- B. Carrier arms.
- (1) Latching levers.
- (2) Locking mechanism.
- C. Bumpers.
- D. Operation.

II. Modification shown in Figs. 13 to 21.

- A. Shuttle.
- B. Carrier arms.
- (1) Latching levers.
- (2) Locking mechanism.
- C. Operation.
- D. Safety mechanism.
- E. Guiding mechanism.

III. Shuttle details.

I. Embodiment shown in Figs. 1 to 10

A. Shuttle.—The shuttle 31 includes a bobbin compartment 38 and an open-ended lateral housing 39 (see Figs. 3, 4, 5 and 7), the latter being formed of plates or flanges 40 extending laterally of the bobbin compartment, which flanges, as shown, may be integral with the outer wall of said compartment. The outer ends 42 of the plates or flanges 40 are bent toward each other as shown in Fig. 7 so as to be parallel with a vertical wall 43 which separates compartment 38 from housing 39.

Fixedly mounted within the housing are an outer and an inner set of guides, forming vertically aligned outer guiding channels 44 and similarly aligned inner guiding channels 44', respectively (see Fig. 7), the purpose of which will be explained hereinafter. The inner set of guides (i. e. that nearer the bobbin compartment) is composed of the oppositely positioned members 45 and 45' located near the right end of the open-ended housing as viewed in Fig. 3, and the oppositely positioned members 46 and 46' mounted near the left end of the housing. The outer set of guides is similarly composed of the members 47 and 47', and 48 and 48'. As is shown in Figs. 3, 4 and 6, each of the guiding members extends for only a short distance longitudinally of the shuttle. The guiding members 45 and 45' are spaced vertically farther apart from each other than are the members 46 and 46'; while the members 47 and 47' are vertically farther apart from each other than are 48 and 48'. Fig. 7 shows the more closely spaced members 46, 46' of the inner set and the more distantly spaced members 47, 47' of the outer set. It will be understood that the more distantly spaced guiding members 45, 45' of the inner set are located forwardly (toward the reader) of members 46, 46'; while the more closely spaced members 48, 48' of the outer set are similarly positioned with respect to members 47, 47'. As will be clear from Fig. 7, the portions of the guiding

channels defined by the more distantly spaced members 45, 45' and 47, 47' are wider than the portions defined by the more closely spaced members 46, 46' and 48, 48'. The object of this construction will become apparent in connection with the description hereinbelow of the carrier arms, and the manner in which they engage with and support the shuttle.

Upon the bottom flange 40 of the housing 39 are fixedly mounted to latch plates 49 and 50 spaced from each other in parallel relation and symmetrically positioned with respect to the central axis of the housing (Fig. 7). As illustrated, the plates may, in cross-section, form the parallel arms of a Y and be supported by a common stem 51 which may be flanged at its bottom and secured to the bottom flange 40 in any well-known manner, as by welding, riveting, etc. The inner latch plate 49 is provided with projecting, upwardly extending lugs 52 and 53, and the outer plate 50 is similarly provided with lugs 52' and 53' in alignment, respectively, with lugs 52 and 53. Between the latch plates 49 and 50 is a guideway or channel 54 for receiving the latching levers mounted on the carrier arms to be described below.

The outer surfaces of the aligned lugs 52, 52' are shaped in the form of cams having inclined surfaces 55, 55'. The lugs 53 and 53' have similar inclined cam surfaces 57, 57'. The inner opposing faces of the lugs 52, 53 are slightly inclined to the vertical as shown in Figs. 3 and 4.

The above described guiding means and latch plates cooperate with the rest of the latching mechanism mounted upon the carrier arms (which will be described immediately) to guide said arms within the housing 39, the latch plates being engaged by the latching mechanism on said arms during the transfer of the shuttle from one arm to the other. The other parts of the shuttle shown in Figs. 1, 2, 6, 7, 8, 11 and 12 are not necessary to an understanding of the shuttle latching devices and will be described farther on in the specification.

B. Carrier arms.—Connected to the carriers 32 in any suitable way, as by means of contiguous flanges or walls bolted together, are members 59 and 59' of partially tubular form. These members roughly define housings which are open at 60, 60' and 61, 61' and include walls 62 and 62', respectively, extending in the direction of the carriers 32 (see Fig. 5). Attached to the wall 62 exteriorly thereof is a carrier arm 63 while a similar arm 63' is attached to wall 62' but interiorly thereof. The arms 63, 63' thus extend toward each other and are offset with respect to each other transversely of the machine, and are so dimensioned that they overlap for the major portion of their length at the end of their inward movement. It will be understood that the arms 63, 63' are simi-

larly constructed and that the corresponding parts attached thereto are symmetrically arranged with respect to a vertical plane parallel to the arms and extending midway between them; and further, that the numerals with the prime attached thereto refer to the inner arm and the parts attached thereto, while the numerals without such prime refer to the outer arm and its associated parts. The arms are composed of rear sections 64, 64' of greater height and forward sections 65, 65' of lesser height, the same being connected by tapered portions 66, 66'. The height of the sections 64, 64' is equal to the vertical distance between the more distantly spaced guiding members 47, 47' and 45, 45' in the shuttle housing 39; while the height of the sections 65, 65' is equal to the vertical distance between the more closely spaced guiding members 48, 48' and 46, 46'. As is clearly shown in Fig. 5, the sections 64, 64' are of greater width than sections 65, 65', and the widths of the sections 64, 64' and 65, 65' are approximately equal to the widths of those portions of the guiding channels 44 and 44' which are defined by the more distantly spaced guiding members 47, 47' and 45, 45' and by the more closely spaced members 48, 48' and 46, 46', respectively. The larger and wider sections of the arms 63 and 63' are adapted to be received in the larger and wider portions of the channels 44 and 44' respectively, while the smaller and narrower sections are received in the smaller and narrower portions of said channels. The sections 65, 65' terminate in ends 66, 66' of reduced width which taper to a point as shown in Figs. 3 and 4.

B. (1) Latching levers.—Pivotedly mounted at 67 upon arm 63 and arranged adjacent the inner face thereof is a latching lever 68, preferably of I-beam cross-section; and pivoted at 67' upon arm 63' but arranged adjacent the outer face thereof is a similar lever 68'. As seen in Fig. 5, the levers are located in the same vertical planes. The levers are duplicates of each other and terminate in a pair of vertically spaced jaws 69, 70 and 69', 70' respectively, which bear a resemblance to alligator jaws. The upper or releasing jaws 69, 69' extend forwardly of the lower jaws and are provided with upper and lower cam surfaces 71, 71' and 72, 72'. As shown in the drawings, the lower surface 72 or 72' of one jaw is shaped to engage gradually and ride on the upper cam surface 71' or 71 respectively, of the other jaw as they approach the center of the machine during the reciprocation of the carriers 32. The lower or latching jaws are provided with laterally extending hooks 73, 73' so dimensioned as to be capable of bridging the guide-way 54 between the latch plates 49 and 50 of the shuttle housing 39 and engaging the cam surfaces 55, 55' and 57, 57' respectively. 120 125 130

The rearward surfaces 74, 74' of the hooks are slightly inclined to the vertical so as to mate with the inner faces of the lugs 52, 52', 53, 53'. Extending for a short distance below the hooks 73, 73' are guiding webs 75, 75'.

5 Stops 76 and 76' (Fig. 10) fixed to the carrier arms are arranged to be engaged by extensions 77, 77' on the latching levers 68, 68' to limit the downward pivotal movement of the levers in their idle non-latching position 10 while guiding brackets 78, 78' likewise fixed to the arms prevent lateral play of said levers.

15 *B. (2) Locking mechanism.*—As mentioned above, the forward ends of the upper jaws 69, 69' of the latching lever are designed to engage and cam each other, for a purpose to be described below. As the machine is operated at high speed, the danger exists that the levers will be flung upwardly and will not be in proper position for engaging 20 each other as they approach the center of the machine. Means are therefore provided for locking the levers against the stop bars 76, 76', which means are adapted to be released 25 prior to the shuttle transfer as said levers approach the central position. In the present form of the invention, such locking mechanism includes an angular lever 79 having a locking arm 80 and a release or control arm 81 (see Figs. 3, 4, 5 and 9). The lever 79 is pivoted upon a stud 82 anchored upon the section 64 of the arm 63 and is constantly urged 30 by a spring 83 to a position wherein the locking arm 80, which is bent out of the plane of arm 81 as shown in Fig. 9, overlies a projection 84 on the latching lever 68, the said projection being below the stud 82 and approximately in vertical alignment therewith. In 35 this position the locking arm operates as a rigid stop to limit upward swinging movement of the latching lever 68. A stop pin 85 limits the movement of arm 80 under the action of spring 83. The end of the release arm 81 is provided with a roller 86 which projects 40 into the path of movement of the forward end of arm 63.

45 The hub of the angular lever 79 bears against a sleeve 87 fitted upon the stud 82 and is locked upon the latter by means of a locking plate 88 which engages the free end of the stud 82. This plate extends rearwardly and is bent at a point behind stud 82 toward the arm 63 (see Fig. 9), then is bent parallel therewith to form a section 89 resting against said arm; it is then bent forwardly and finally downwardly, the bifurcated end 90 thereof engaging the pivotal stud 67 and thereby locking the hub of the latching lever 68 thereon. The plate 88 is removably fastened to the arm 63 by any suitable means, as by a screw 92. It will be evident that upon removal of the screw and disengagement of plate 88 from studs 82 and 67, the locking lever and latching lever may be easily removed from the mechanism for replacement or repair.

It will be understood that a locking mechanism similar to the above is associated with the arm 63', corresponding parts being indicated by the same numerals but with a prime attached, except that the parts will be arranged symmetrically with respect to a vertical plane passing through levers 68 and 68' and also through a vertical plane passing through the longitudinal axis of the machine.

70 *C. Bumpers.*—The mechanism for pushing 75 the shuttle from the side of the machine to which it has been carried by the arm to which it is latched back to the center of the machine comprises a bumper composed of a block 93 slidably mounted upon a pair of horizontally extending posts 94 mounted within the housing 59. The block is urged outwardly by a pair of springs 95 coiled around said posts. Upon the outer face of the block 93 is a resilient cushion 96 made of rubber or 80 similar material. This cushion is directly in line with an abutment 97 projecting externally of the shuttle housing. The outward movement of the bumper is limited by a pin 98 extending within an aperture 99 in a rearward extension 100 of the block 93. It will 85 be understood that a similar mechanism is arranged within the housing 59' and that a similar abutment 97' is located upon the opposite side of the shuttle. The transverse 95 walls of the housings 59, 59' are apertured at 99^a, 99^a to receive the ends of the shuttle as shown in Fig. 5.

90 *D. Operation.*—The operation of the mechanism thus far described is as follows: It will 100 be assumed that the shuttle is in latched position upon the outer arm 63 and is being pushed forward by the bumper 93 toward the center of the machine as shown in Fig. 3. As 105 is clearly shown in said figure the hook 73 of the latching lever 69 is in position between the lugs 52 and 53 and rests upon the surface which connects these lugs in such a manner that the jaw 69 is held above the jaw 69' of the other latching lever 68' which is idle and 110 is resting in its lowermost position upon the stop 76'. The locking arm 80 is positioned above the projection 84 while the locking arm 80' is positioned above the projection 84', there being some clearance between 80' and 115 84' due to the fact that the latching lever 69' is in its lowermost position. The roller 86 of the release arm 81 extends into the path of the front tapered end of the arm 63' while the roller 86' of the release arm 81' extends 120 into the path of the tapered end of arm 63. As the arms continue to approach each other the release arms 81, 81' will be rocked by the forward ends of the arms 63', 63, thereby removing the locking arms 80, 80' from 125 above the projections 84, 84', thus enabling latching levers 68, 68' to swing upwardly. Immediately upon such release of said levers 68, 68', the hook 73' of lever 68' engages the 130 gently inclined cam surfaces 57, 57' and pro-

ceeds to ride thereupon. The cam surface 71' at the forward end of the releasing jaw 69' then engages the lower cam surface 72 upon the forward end of the corresponding jaw 69. 5 and as the hook proceeds to ride up the cam surfaces 57, 57', the jaw 69, by the cooperation of cam surfaces 71' and 72, is lifted and the hook 73 of the latching lever 68 is raised from in front of the lug 52. As can be seen 10 from said Fig. 3, the parts are so arranged that a slight clearance will exist between the front face of lug 52 and the opposing face of hook 73 so as to facilitate the raising of the hook from in front of the lug. As the 15 hook 73 clears the top of the lug 52, the hook 73' drops by gravity to a position in front of the lug 53. The parts have by this time reached their central position and the return stroke to the side of the machine is about to 20 take place. Upon movement of the arm 68' toward its side of the machine as shown by the right-hand arrow in Fig. 4, the hook member 73' by engagement thereof with the lug 53 will pull the shuttle toward said side 25 of the machine.

It will be seen from Fig. 3 that the reduced section 65 of the arm 63 which is latched to the shuttle is located between the guides 48, 48' and contacts with the same. Similarly 30 the section 64 of increased height is positioned between the more distantly spaced guides 47, 47' and similarly contacts therewith. In this manner the shuttle is supported upon the arm to which it is latched. Referring now to the 35 arm 63' in said Fig. 3, it will be seen that the reduced end 65' of said arm is located between the more distantly spaced guides 45, 45' and therefore does not contact the same at this position of the arm relatively to the shuttle. 40 However, as said arm continues to move toward the center of the machine the section 65' enters the section of channel of reduced height and width defined by the guide members 46, 46' while at the same time the enlarged section 64' enters the section of the 45 channel of enlarged width and height defined by the guide members 45, 45'. It will be evident that by virtue of this construction the arms will engage with the bounding surfaces 50 of the guiding channels only toward the end of their motion toward the center of the machine so that friction between the parts will be reduced to a minimum. Similarly, when the arm 63 becomes disengaged from the 55 shuttle, after the transfer of the latter from the latching mechanism of arm 63 to that of the other arm has been effected as above described, the sections 64, 65 will become completely disengaged from the bounding surfaces of the channel 44 after only a small 60 movement thereof relatively to the shuttle.

II. Modification shown in Figs. 13 to 21

The differences between the modification 15 shown in Figs. 13-21 and the embodiment

above described, which relate to the operation of the latching levers, will first be given, and after the operation has been explained the other variations will be described.

A. Shuttle.—Referring to Figs. 13 and 14, 70 the shuttle 101 is provided with latch plates 49, 50 similar to those on shuttle 31 described above, the homologous parts being similarly designated. The shuttle 101, is however, additionally provided with a cam plate 102 75 fixed to the shuttle and lying directly above the guideway 54 so as to be in the plane of the latching levers. The cam plate is provided with oppositely inclined cam surfaces 103, 104 and 103', 104' (see Fig. 15), the function of which will be explained below.

B. Carrier arms.—The carrier arms in this form of the invention are of the same general form as those shown in Figs. 1 to 5. As shown in Fig. 13, the arms may be of skeleton 85 form to reduce their weight.

B. (1) Latching levers.—The latching levers 105, 105' shown in Figs. 13-21 are, like the corresponding levers 68, 68', pivoted upon the carrier arms and are provided with upper 90 releasing jaws 69, 69' and lower latching jaws 70, 70', the latter having the hooks 73, 73', and the guiding webs 75, 75'. (It will be obvious that as Figs. 13-21 are viewed from the reverse side relative to Figs. 1-5, the inner arm will be mounted at the left in Figs. 13-21 and the position of the numerals with prime attached will therefore be reversed.) The cam surfaces 71, 71' and 72, 72' on the upper releasing jaws differ somewhat from the corresponding surfaces of the jaws shown in Figs. 3 and 4, in that while in the latter figures the upper surfaces 71, 71' are inclined, while the lower surfaces 72, 72' are substantially horizontal, the reverse 100 is true of the modification embodied in Figs. 13-21. It will be understood, however, that the form of these cam surfaces may be varied to conform to any desired curves provided only that a lifting action is exerted by one 105 lever on the other as they are moved into engagement when they are out of alignment as shown in Figs. 3 and 16. Projecting above the releasing jaws 69, 69' at a point removed from the forward ends thereof are cam 110 fingers 106, 106' whose purpose will be described below. The latching levers are guided in their vertical movements by guides 78, 78' and in their idle position rest upon stops 107, 107' projecting from the carrier 115 arms, their upward motion being limited by pins 108, 108' likewise fixed to said arms.

B. (2) Locking mechanism.—The mechanism for locking the latch levers in position to prevent premature upward movement 120 thereof comprises angular levers 109, 109' pivoted at one end upon studs 110, 110' fixed upon the carrier arms. Pins 111, 111' project from the angular portion of levers 109, 109' and are arranged to engage curved sur- 125

faces 113, 113' (Fig. 13) on the top of latching levers 105, 105'. The angular levers 109, 109' are urged inwardly by springs 114, 114' being limited in their forward movement, 5 when the latching levers are in lowered idle position, by portions 115, 115' of the surfaces 113, 113', which portions are non-concentric with respect to studs 110, 110'. The curved surfaces are so formed that the pins 111, 111' will engage a portion thereof to lock the latching levers both when the latter are in raised latching position and when they are in lowered idle position. As is evident from Fig. 13, the pins 111, 111' will engage a more 15 rearward portion of said curved surfaces when the levers 105, 105' are in latching position, due to the fact that the latching levers oscillate in a path which is eccentric to the pivotal center of the levers 109, 109'. At the 20 free ends of the levers 109, 109' are mounted rollers 115^a and 115^b which project into the path of the forward ends of the opposite carrier arms. A spring 116, 116' coiled about studs 117, 117' is anchored at one end upon the carrier arms and at its other end engages the respective latching levers 105, 105' to urge the same against their respective lower 25 stops 107, 107'. The locking levers and the latching levers are locked upon their respective pivot studs by means of locking bars or plates 118, 118' having bifurcated ends which embrace the said studs, the bars being removably fastened to the carrier arms by means of rivet 119, 119' or by any other suitable fastening means.

C. Operation.—The operation of the modification disclosed in Figs. 13-21 is as follows: Assuming that shuttle 101 is resting upon and is latched to the latching lever 105 as shown in Fig. 13, it will be seen that the said latching lever is locked against vertical movement by the pin 111 and is at the same time held in position in front of lugs 52' by means of the spring 116. The idle latching lever 105' in this position of the mechanism rests upon its bottom stop 107' being urged downwardly by the spring 116' and locked against upward movement by the pin 111' upon locking lever 109'. Referring to Figs. 16-21 which illustrate the shuttle transfer movement by steps in several successive positions of the mechanism, it will be seen from Fig. 16 that, after the forward ends of the carrier arms have passed beyond the center 45 of the machine, they engage the rollers 115^a, 115^b, respectively, and thereby swing the levers 109, 109' so as to disengage the pins 111, 111' from the surfaces 113, 113'. Immediately upon such release of the locking levers 50 the hook 73' of latching lever 105 begins to ride upon the gently inclined surfaces 57, 57' of latching plates 49, 50 as shown in Figs. 16 and 17. The lever 105' is thereupon raised and the forward end of the releasing jaw 69' 55 engages the under surface 72 of the releasing

jaw 69 of the latched lever 105. As the latching levers continue to approach each other the hook 73' continues to ride upon the inclined surfaces 57, 57' and the releasing jaw 69' raises the locking jaw 70 of the latched lever, and the latter is lifted as shown in Fig. 17 until its hook 73 clears the forward face of the lugs 52, 52'. At the same time the cam finger 106 engages the inclined cam surface or stop 103 on the cam plate 102 and serves thereby to position the shuttle properly with respect to the latching levers. Fig. 18 shows the parts in their central position, the carrier actuating mechanism having completed its inward stroke. In this position of the parts 70 it will be seen that the lever 105 has been completely disengaged from the latch plates 49, 50, and that the lever 105' is in position to drop with its hook 73' in front of lugs 53, 53'. 75

Figs. 19-21 show the latching levers on their return stroke to the side of the machine. As the lever 105 moves farther to the right as shown in Fig. 19, the top of the cam finger 106 engages the inclined surface 104 which, as the lever continues its movement to the right, exerts a downward push thereon. At the same time the releasing jaw 69' withdraws from between the jaws 69, 70 of said last-mentioned lever, but as it withdraws, a downward push is exerted thereon by the jaw 69 due to the camming action of surface 104 upon finger 106. This downward push is transmitted to the latching jaw 70' and insures the dropping of hook 73' in front of lugs 53, 53'. At about this time the forward ends of the carrier arms become disengaged from the rollers 115^a, 115^b and the locking levers 109, 109' are returned by springs 114, 114' to operative position to lock the latching levers against upward movement. By the time that the releasing jaws become disengaged from each other as shown in Fig. 20 the hook 73' has been positively moved into complete locking engagement with lugs 53, 53'. It will be understood that the spring 116' acts along with the cooperating cams 105, 104 to urge the latching jaw 70' into locking engagement with said lugs. 100

D. Safety mechanism.—During the continuous operation of the machine the action of locking levers 109, 109' may become uncertain through fatigue or breakage of the springs 114, 114' or said levers may become caught or broken so as to be entirely ineffective upon latching levers 105, 105'. In such event the lever 105', as shown in Fig. 15, is likely to be thrown upwardly against its upper limiting stop, in which case it will not be in proper operative relation with respect to the latched lever 105 to unlatch the same. To provide for such contingencies, a safety mechanism in the form of a cam piece 119, 119' is provided, which cam pieces are hinged upon the ends of the cam plate 102 in such 105 110 115 120 125 130

manner that an inclined cam surface 120, 120' is interposed in the path of the releasing jaws. As shown in Fig. 15, upon movement of the latching levers toward each other and toward the center of the machine the forward end of the releasing lever 69' engages this cam surface 120' and is forced by the latter to assume the proper operative position shown in Fig. 16 with respect to the latched lever 105, such proper position being further insured by the engagement of the cam finger 106' with said cam surface. The cam pieces are so mounted as to be rigid in an inward direction (i. e. toward the center of the machine) but will swing freely in the reverse direction. The cam pieces 119, 119', upon return of the latching levers to the side of the machine, are swung upwardly as shown in Fig. 20.

E. Guiding mechanism.—The guiding mechanism in the modified form of the invention may be of the same type as that shown in Figs. 3, 4, 5 and 7, but in the present instance is shown as being composed of two bands 122, 122' extending outwardly from the bobbin compartment 38 of the shuttle 101 (see Fig. 14). Extending between and centrally of these bands and attached thereto is the cam plate 102 while directly below the latter are the latching plates 49, 50. The two bands are provided with guiding channels defined by guiding members constructed and arranged similarly to the guiding members shown in said Figs. 3, 4, 5 and 7. The carrier arms are likewise constructed similarly to the arms heretofore described and engage the guiding members in the same way.

III. Shuttle details

The shuttle, as shown in the drawings, is of elongated form and the ends thereof taper to a point as shown at 125. The purpose of this construction is to enable the forward end of the shuttle to cam upwardly any loose warp threads that may be in its path and thus avoid breaking or entanglement of such threads. The angular portions 37 of the carrier arms are curved for the same reason.

The shuttle is open at the top as indicated at 126 to permit the insertion therein of a bobbin 127 composed of thread wound on a core 128, which is adapted to fit over a spindle 129 pivoted at 130 within the bobbin compartment 38 of the shuttle. The bobbin core 128 is held against rotation on said spindle by means of flanges 131 which project from an end of the core and engage pins 132 fixed upon an enlarged portion of the spindle. The hub of the spindle is provided with a lug 133 and with a slot or depression 134 which are arranged to be engaged by a spring detent 135 fastened to a bracket 136 rigidly mounted within the shuttle and adapted to hold the spindle resiliently either in operative position with the bobbin thereon, as shown

in full lines in Fig. 8, or in inoperative position, as shown in dotted lines, projecting through the opening 126 of the shuttle for the insertion or removal of a bobbin. A tail-piece 137 on the hub of the spindle is arranged to engage a projection 138 on the bracket 136 to limit the downward movement of the spindle. The opening 126, at its end farthest from the spindle support, communicates with an inclined slot 126^a upon the front face of the shuttle (see Figs. 2 and 6) which slot terminates in a substantially horizontal section 126^b.

Attached to the shuttle externally thereof and at the side opposite to the housing 39 is a tension mechanism housing 138' including an outer plate or wall 139 and an inner plate or wall 140. The housing is open at the top as shown at 141, and the outer and inner walls are slotted at 142, the slots extending substantially horizontally, then turning downwardly and merging with openings 143 extending through the walls in alignment with each other. The outer and inner walls are joined together in V fashion at their free ends as shown at 144 in Fig. 1. A tension lever 145 having a bearing 146 thereon is journaled in the walls 139, 140. The lever is in general of channel shape (see Figs. 11 and 12) having a web or top portion 147 and side flanges 148. The web 147 is depressed longitudinally to form a channel 149 and is notched transversely as shown at 150. A finger 151 formed with a semicircular bend at 152 passes through an opening in the web 147 at the side of the notch farther from bearing 146, the arm 153 of the finger being connected, as by welding, to the under side of the web. As shown in Fig. 11, the bend 152 of finger 151 overlies the notch 150 so as to form a substantially circular opening therewith. The portion of the bend opposite arm 153 fits within channel 149 so that the circular opening offers no egress to a thread or yarn extending therethrough; in other words, such yarn, when once threaded into the opening, cannot accidentally slip back into the channel 149. The other arm 154 of the finger 151 is curved upwardly away from the web 147 in such a manner as to effect raising of lever 145 when a yarn stretched across slots 142 presses against the finger. Fitted about the openings 143 and attached to the walls 139, 140 externally thereof are liners 155 for guiding the thread as it passes through said openings.

The yarn is threaded through the tensioning mechanism in the following manner: The forward end of the yarn which is unwound from the bobbin 127 is passed around a guiding member 155^a (Fig. 1), through slot 126^a, 126^b, then pulled through the space 156 (Fig. 7) between the inner wall and the front face of the shuttle. The yarn is then reversely looped in front of the common or V end 144

of the walls 139, 140, and engaged in the horizontally registering slots 142 below said V end. The thread is pulled rearwardly, resting on the lower side of slots 142, and as the loop moves rearwardly it raises the finger 151, thereby also raising lever 148, as shown in dotted lines in Fig. 6, until the channel 149 is approximately on a level with the slots 142, whereupon the loop of yarn enters said channel and passing rearwardly through the same 5 engages the under side of the bend 152. The manually produced tension in the yarn is then released and the lever 148 and the finger 151 drop by gravity, the yarn passing through 10 the vertical portions of slots 142 and finally engaging the under sides of the openings 143. It will thus be seen that when threaded through the tension mechanism, the yarn passes from between the inner wall 140 and 15 the front face of the shuttle through the opening 143 in said inner wall, into the housing 138 beneath the bend 152 of finger 151 and out through the opening 143 in the outer wall 139, the liners 155 serving to guide and 20 provide an extended supporting surface for 25 the yarn. As the yarn is unwound from the bobbin and laid across the warp threads in the shed, the weight of the tension lever 145 thereon produces a constant and uniform tension on the thread.

The various parts of the mechanism above described, including the shuttle transfer devices, the shuttle and the tensioning mechanism, may be made of sheet metal, producing 30 a structure of small weight which is easy and inexpensive to manufacture. It will be clear from the operation of the device that we have provided a mechanism whereby the shuttle is transferred across the shed in a positive and 35 uniform manner along a definite path and is always under the control of the transfer mechanism. Our mechanism is so constructed that the transfer of the shuttle from one arm to the other is effected in a gradual manner free 40 from shock and impact, whereby the stresses on the machine and the noises are reduced to a minimum. The carriers and carrier arms are of simple construction and the latter are completely and compactly housed within 45 50 lateral extensions on the shuttle during the shuttle transfer. The shuttle is securely supported by the arm to which it is latched in a manner free from binding action and the shuttle arms are so formed and dimensioned 55 as shown in the drawings, that should any loose warp threads hang down in the shed, they will be cammed away from the latching mechanism by a forward tapered end 60 of either the shuttle or the idle arm so that entanglement or breaking of the yarn is prevented. As shown in Figs. 3 and 13, the outer ends of the housings 59, 59' are curved 65 upwardly for the same purpose. Our mechanism further includes positive locking means

and safety devices to insure proper engagement of the latching elements.

Our invention embraces also a novel form of shuttle designed to cooperate efficiently with the latching mechanism and provided with a novel form of bobbin support and with a novel tensioning mechanism through which the yarn can be quickly and easily threaded and which exerts a positive and uniform tension on said yarn.

Variations may be resorted to within the scope of the claims without departing from the spirit of the invention.

We claim:

1. In a loom, the combination of a shuttle having a bobbin compartment and an open-ended housing arranged laterally thereof, a pair of carrier arms movable toward and away from each other and disposed in offset relations, guiding members in said housing defining guiding channels for said arms within which the latter fit, said arms being adapted to support said shuttle in alternate sequence, latching mechanism on said shuttle, and latching members on said arms arranged to lock alternately with said mechanism whereby the shuttle is transferred from one arm to the other and vice versa.

2. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

3. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

4. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

5. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

6. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

7. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

8. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

9. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

10. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

11. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

12. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

13. In a loom, the combination of a shuttle having a bobbin compartment and an open-ended housing arranged laterally thereof, a pair of carrier arms movable toward and away from each other and disposed in offset relation, guiding members in said housing defining guiding channels for said arms, said arms being adapted to support said shuttle in alternate sequence, latching mechanism on said shuttle, and latching members on said arms arranged to lock alternately with said mechanism whereby the shuttle is transferred from one arm to the other and vice versa.

for releasing said locking mechanism prior to the shuttle transfer.

4. In a loom, the combination of a shuttle having a bobbin compartment and an open-ended housing arranged laterally thereof, a pair of carrier arms movable toward and away from each other and arranged in offset relation, guiding members in said housing defining guiding channels for said arms within which the latter fit, said arms being adapted to support said shuttle in alternate sequence, latching mechanism on said shuttle, latching members on said arms arranged to lock alternately with said mechanism whereby the shuttle is transferred from one arm to the other and vice versa, locking mechanism for said latching members, and means for releasing said locking mechanism prior to the shuttle transfer, said locking mechanism including a locking arm pivoted upon each carrier arm and arranged in the path of movement of the associated latching member and positionable substantially at right angles to the longitudinal axis of said member.

5. In a loom, the combination of a shuttle having a bobbin compartment and an open-ended housing arranged laterally thereof, a pair of carrier arms movable toward and away from each other and arranged in offset relation, guiding members in said housing defining guiding channels for said arms within which the latter fit, said arms being adapted to support said shuttle in alternate sequence, latching mechanism on said shuttle, latching members on said arms arranged to lock alternately with said mechanism whereby the shuttle is transferred from one arm to the other and vice versa, locking mechanism for said latching members, and means for releasing said locking mechanism prior to the shuttle transfer, said locking mechanism including a locking arm pivoted upon each carrier arm and arranged in the path of movement of the associated latching member and positionable substantially at right angles to the longitudinal axis of said member, and said releasing means including a release arm connected to said locking arm and extending into the path of movement of the other carrier arm to be rocked thereby to withdraw said locking arm from the path of movement of said member.

6. In a loom, the combination of a shuttle, a pair of carrier arms movable toward and away from each other in offset relation and adapted to support said shuttle in alternate sequence, latching mechanism on said shuttle, latching members on said arms arranged to lock alternately with said mechanism whereby the shuttle is transferred from one arm to the other and vice versa, positive locking mechanism for said members for preventing premature movement thereof mounted on said arms, and means for releasing said locking mechanism prior to the shuttle transfer.

7. In a loom, the combination of a shuttle, a pair of carrier arms movable toward and away from each other in offset relation and adapted to support said shuttle in alternate sequence, latching mechanism on said shuttle, movable latching members on said arms arranged to lock alternately with said mechanism whereby the shuttle is transferred from one arm to the other and vice versa, positive locking mechanism for said members for preventing premature movement thereof, and means for releasing said locking mechanism prior to the shuttle transfer, said locking mechanism including a rigid locking arm pivoted upon each carrier arm and arranged in the path of movement of the associated latching member and positionable substantially at right angles to the longitudinal axis of said member.

8. In a loom, the combination of a shuttle, a pair of carrier arms movable toward and away from each other in offset relation and adapted to support said shuttle in alternate sequence, latching mechanism on said shuttle, latching members on said arms arranged to lock alternately with said mechanism whereby the shuttle is transferred from one arm to the other and vice versa, positive locking mechanism for said members for preventing premature movement thereof, and means for releasing said locking mechanism prior to the shuttle transfer, said locking mechanism including a locking arm pivoted upon each carrier arm and arranged in the path of movement of the associated latching member and positionable substantially at right angles to the longitudinal axis of said member, and said releasing means including a release arm connected to said locking arm and extending into the path of movement of the other carrier arm to be rocked thereby to withdraw said locking arm from the path of movement of said member.

9. In a loom, the combination of a shuttle, a pair of carrier arms movable toward and away from each other and arranged to support said shuttle in alternate sequence, lugs mounted on said shuttle, and latching members on said arms adapted alternately to engage said lugs and to be operated one by the other and released from said lugs whereby said shuttle is automatically transferred from one carrier arm to the other and vice versa, said latching members each including a latching jaw adapted to engage said lugs and a releasing jaw adapted to be engaged by the releasing jaw of the other member to unlatch the associated latching jaw from said lugs.

10. In a loom, the combination of a shuttle, a pair of carrier arms movable toward and away from each other and arranged to support said shuttle in alternate sequence, a pair of spaced aligned cam plates fixed on said shuttle and forming a guideway therebetween, lugs on said plates, latching levers

pivoted on said arms in co-planar relation and in the plane of said guideway, hooks on said levers arranged to contact the cam surfaces of said cam plates and to span said guideway, said hooks cooperating with said lugs to latch the shuttle to said arms alternately and a releasing element on each of said latching levers adapted, as its associated hook engages said cam surfaces, to lift the other lever out of latching engagement with said lugs.

11. In a loom, the combination of a shuttle, a pair of carrier arms movable toward and away from each other and arranged to support said shuttle in alternate sequence, a pair of spaced aligned cam plates fixed on said shuttle and forming a guideway there-between, lugs on said plates, latching levers pivoted on said arms to co-planar relation 15 and in the plane of said guideway, hooks on said levers arranged to contact the cam surfaces of said cam plates and to span said guideway, said hooks cooperating with said lugs to latch the shuttle to said arms alternately, a releasing element on each of said latching levers projecting forwardly of its associated hook and adapted, as said hook engages said cam surfaces, to lift the other lever 20 out of latching engagement with said lugs, 25 and a guiding web projecting below each of said hooks and adapted to enter said guideway to position said levers in operative relation to each other.

12. In a loom, the combination of a shuttle,
35 a pair of carrier arms movable toward and
away from each other and arranged to sup-
port said shuttle in alternate sequence, lugs
mounted on said shuttle, movable latching
members on said arms, said members includ-
40 ing latching hooks and forwardly extending
releasing elements, and adapted alternately
to engage said lugs and to be operated one
by the other and released from said lugs
whereby said shuttle is automatically trans-
45 ferred from one carrier arm to the other and
vice versa, locking mechanisms mounted on
said arms for locking said members in latch-
ing or in idle position and means for releasing
said locking mechanisms prior to the un-
50 latching of the latching member.

13. In a loom, the combination of a shuttle, a pair of carrier arms movable toward and away from each other and arranged to support said shuttle in alternate sequence, lugs mounted on said shuttle, latching members on said arms, said members including latching hooks and forwardly extending releasing elements, and adapted alternately to engage said lugs and to be operated one by the other and released from said lugs whereby said shuttle is automatically transferred from one carrier arm to the other and vice versa, locking mechanisms for locking said members in latching or in idle position, each of said locking mechanisms comprising a locking arm

pivoted on the carrier arm and movable to a position approximately at right angles to the longitudinal axis of the associated latching member to prevent upward swinging movement thereof, a control arm rigidly connected to said locking arm and having a portion thereof projecting into the path of the other carrier arm, and a cam upon the forward end of each carrier arm adapted to engage the projecting portion of said control arm to swing said locking arm away from the associated latching lever prior to the unlatching of the latched member.

14. In a loom, the combination of a shuttle, a pair of carrier arms movable toward and away from each other and arranged to support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, positioning elements associated with said latching members for resisting upward movement thereof, and means for directing said members into proper releasing position upon failure of said positioning elements. 9

15. In a loom, the combination of a shuttle, a pair of carrier arms movable toward and away from each other and arranged to support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, positioning elements associated with said latching members for resisting upward movement thereof, and means for directing said members into proper releasing position upon failure of said positioning elements, said last-mentioned means including a cam mounted on said shuttle and engageable by a latching member when the latter is in abnormally raised position.

16. In a loom, the combination of a shuttle, a pair of carrier arms movable toward and away from each other and arranged to support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, positioning elements associated with said latching members for resisting upward movement thereof, and means for directing said members into proper releasing position upon failure of said positioning elements, said last-mentioned means including a cam pivoted upon the shuttle and engageable by a latching member when the latter is in abnor-

mally raised position, said cam being rigid in an inward direction but swingable outwardly in the opposite direction out of the path of the latching member.

- 5 17. In a loom, the combination of a shuttle, a pair of carrier arms movable toward and away from each other and arranged to support said shuttle in alternate sequence, lugs mounted on said shuttle, latching members on 10 said arms, said members including latching hooks and forwardly extending releasing elements, and adapted alternately to engage said lugs and to be operated one by the other and released from said lugs whereby said 15 shuttle is automatically transferred from one carrier arm to the other and vice versa, locking mechanisms for locking said members in latching or in idle position, each of said locking mechanisms comprising a locking 20 arm pivoted on the carrier arm and movable to a position approximately at right angles to the longitudinal axis of the associated locking member to prevent upward swinging movement thereof, a stop, a spring urging 25 said locking arm against said stop to determine the locking position of said arm, a control arm rigidly connected to said locking arm and having a portion thereof projecting into the path of the other carrier arm, a cam 30 upon the forward end of each carrier arm adapted to engage the projecting portion of said control arm to swing said locking arm away from the associated latching lever prior to the unlatching of the latched member, and 35 cam-pieces mounted upon said shuttle in the plane of said latching levers and adapted to cam said levers into proper releasing position upon failure of said locking mechanism.
18. In a loom, the combination of a shuttle, 40 a pair of carrier arms movable toward and away from each other and arranged to support said shuttle in alternate sequence, lugs mounted on said shuttle, latching members on said arms adapted alternately to engage 45 said lugs and to be operated one by the other and released from said lugs whereby said shuttle is automatically transferred from one carrier arm to the other and vice versa, cam surfaces on each of said latching members adapted to cooperate with complementary 50 cam surfaces on the other member whereby, as said latching members approach each other, the latched member is cammed upwardly to clear the lugs on the shuttle, and 55 a pressure exerting element mounted on the shuttle and cooperating with the unlatched member to force the other member into latching engagement with its lug to complete the shuttle transfer.
- 60 19. In a loom, the combination of a shuttle, a pair of carrier arms movable toward and away from each other and arranged to support said shuttle in alternate sequence, lugs mounted on said shuttle, latching members 65 on said arms adapted alternately to engage

said lugs and to be operated one by the other and released from said lugs whereby said shuttle is automatically transferred from one carrier arm to the other and vice versa, 70 said latching members each including a latching jaw adapted to engage said lugs and a releasing jaw adapted to be engaged by the releasing jaw of the other member to unlatch the associated latching jaw from said lugs, 75 cooperating cam surfaces on the upper and lower sides of said releasing jaws whereby, as said latching levers approach each other, the latched jaw is cammed upwardly out of engagement with the lug on said shuttle, a cam plate mounted on said shuttle above said lugs and having inclined cam surfaces thereon, and a cam finger on each of said levers arranged to engage one of said inclined cam surfaces to be cammed downwardly thereby 80 to exert pressure on said releasing jaws to 85 maintain the same in contact during the separating movement of said jaws to force the other latching jaw into engagement with its corresponding lug to complete the shuttle transfer. 90

20. In a loom, the combination of a shuttle, a pair of carrier arms movable toward and away from each other and arranged to support said shuttle in alternate sequence, lugs mounted on said shuttle, latching members 95 on said arms adapted alternately to engage said lugs and to be operated one by the other and released from said lugs whereby said shuttle is automatically transferred from one carrier arm to the other and vice versa, 100 said latching members each including a latching jaw adapted to engage said lugs and a releasing jaw adapted to be engaged by the releasing jaw of the other member to unlatch the associated latching jaw from said lugs, 105 cooperating cam surfaces on the upper and lower sides of said releasing jaws whereby, as said latching levers approach each other, the latched jaw is cammed upwardly out of engagement with the lug on said shuttle, a cam plate mounted on said shuttle above said lugs and having a pair of cam surfaces associated with each latching lever, and a cam finger on each of said levers arranged to contact one of said cam surfaces on the inward 110 stroke as the lever is unlatched from the shuttle to position the latter for transfer to the other lever, the finger being arranged to engage also the other of said pair of cam surfaces as the unlatched lever withdraws from 115 the shuttle to be cammed downwardly thereby, whereby pressure is exerted on said releasing jaws to maintain the same in contact during the separating movement of said jaws to force the other latching jaw into engagement with its corresponding lug to complete 120 the shuttle transfer.

21. In a loom, the combination of a shuttle, a pair of carrier arms movable toward and away from each other and arranged to 125

support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, and a positioning cam fixed to said shuttle and engageable by the unlatched member to position the shuttle in proper relation with respect to the other latching member to be latched thereby.

22. In a loom, the combination of a shuttle, a pair of carrier arms movable toward and away from each other and arranged to support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, and cooperating pairs of cam members on said jaws and on said shuttle alternately operative during the separating movement of said latching members to cam the latching member to which the shuttle has been transferred positively into engagement with its associated lug.

30 23. In a loom, the combination of a shuttle, a pair of carrier arms movable toward and away from each other and arranged to support said shuttle in alternate sequence, lugs mounted on said shuttle, latching members on said arms adapted alternately to engage said lugs and to be operated one by the other and released from said lugs whereby said shuttle is automatically transferred from one carrier arm to the other and vice versa, cooperating pairs of cam members on said jaws and on said shuttle alternately operative during the unlatching operation to position said shuttle with respect to the latching member to which the shuttle is to be transferred, and additional cams on said shuttle operative alternately during the separating movement of said latching members to cam the latching member to which the shuttle has been transferred positively into engagement with its associated lug.

45 24. In a loom, the combination of a shuttle, a pair of carrier arms movable toward and away from each other in offset relation and adapted to support said shuttle in alternate sequence, latching mechanism on said shuttle, movable latching members on said arms arranged to lock alternately with said mechanism whereby the shuttle is transferred from one arm to the other and vice versa, positive locking mechanism for said members for preventing premature movement thereof, and means for releasing said locking mechanism prior to the shuttle transfer, said locking mechanism including a locking arm pivoted upon each carrier arm and arranged in the

path of movement of the associated latching member and positionable substantially at right angles to the longitudinal axis of said member, each of said latching members having a stop thereon provided with an inclined surface adapted to be engaged by said locking arm when said member is in idle or in latching position, whereby said member is locked by said arm in both said positions.
